FRANK H. ILSE, OF DETROIT, MICHIGAN, ASSIGNOR TO JIFFY AUTO CURTAIN COMPANY, OF DETROIT, MICHIGAN, A CORPORATION OF DELAWARE.

CURTAIN.

1,169,160.

Specification of Letters Patent.

Patented Jan. 25, 1916.

Application filed October 31, 1914. Serial No. 869,567.

To all whom it may concern:

Be it known that I, FRANK H. ILSE, a citizen of the United States of America, residing at Detroit, in the county of Wayne and

5 State of Michigan, have invented certain new and useful Improvements in Curtains, of which the following is a specification, reference being had therein to the accompanying drawings.

10 The invention relates to curtain constructions designed for use in connection with vehicle canopy tops and more particularly to the type in which the curtains are strung upon a suspension cable, along which they 15 may be adjusted from position for use to position for storage.

It is the object of the present invention to obtain a construction in which the curtains are more conveniently stored, and also to 20 avoid interference with the collapsing of the canopy top.

In the drawings: Figure 1 is a longitudinal section through a vehicle canopy top to which my improvements are applied; Fig. 2 25 is a perspective view; Fig. 3 is a similar view showing a modified construction; Fig. 4 is a section on line $x-x$ Fig. 1; and Fig. 5 is an elevation of the cable, showing the crimps.

30 In the present state of the art, one type of curtain which has been extensively used on vehicle canopy tops comprises a series of curtain sections which are strung upon a flexible cable, the latter being permanently 35 attached to the vehicle top and extending longitudinally of the sides thereof. The curtains when not in use are folded and slid along the cable to a position beneath the top where they are secured by straps or 40 other fastening devices. It has been found, however, that the stored curtains, though compactly arranged, nevertheless form an obstruction, and furthermore in the collapsing 45 of the canopy top there is more or less interference by the curtains and the attachment cable. With the present invention the curtains are so stored as to be completely out of the way of the occupants of the vehicle, and the attachment cable is also stored so as 50 not to interfere with the collapsing of the canopy top.

In detail, A is a canopy which, as shown, has the inclined rear bow B, the intermediate bow C and front bows D and E.

F is the cable which extends parallel to 55 the lower edge of the "quarter" or depending side of the canopy and upon which the curtains G are strung. As heretofore attached one end of the cable is secured to the inclined rear bow at a point in the plane of 60 suspension and which consequently is in advance of the back plane of the canopy. This limits the rearward movement of the curtains when adjusted to stored position and also holds them in such a position that they 65 interfere more or less with the folding of the bows in the collapsing of the top. The suspension cable also interferes and renders more difficult the operation of collapsing the top, particularly where this is performed 70 by one person.

To avoid the objections just referred to, in place of attaching the end of the cable F to the inclined portion of the rear bow B, I extend the cable to a point H upon the cross 75 bar of said bow, so that in the stored position it will be completely free from the side portions of the bow. I have further provided a pocket J attached to the cross-bar of the bow B, in which the curtains may be 80 stored and which being located adjacent to the rear curtain is out of the way of the occupants of the vehicle.

As it is desirable to have the portion of the cable on which the curtains are suspended 85 when in position for use parallel with the edge of the canopy top, a hooked guide K is secured to the inclined portion of the bow B in the plane of the horizontal portion of the cable. There is also a hooked guide K' 90 on the cross bar of the bow, and to hold the cable taut a spring H' is attached thereto, this being also arranged along the cross-bar of the bow.

It is usual to store the curtains for the 95 front and rear seats in different positions, but with my improved construction all of the curtains may, if desired, be stored in the one pocket J attached to the rear bow. The suspension cable also may be stored by detaching its forward end F' from a stud or button L, and by then folding the cable and 100

laying in the pocket J beside the curtains. This operation is facilitated by forming the cable with crimps M, which divide it into sections of the proper length for folding, and by flattening or thinning the metal at these points it is rendered more flexible for folding. However, when the cable is in use the tension of the spring will hold it taut.

In the modified construction shown in Fig. 3, provision is made for storing the middle and rear curtains in the rear pocket as heretofore described, while the curtains for the forward seat are stored at the front above the windshield. With this construction the cable is made in two lengths having the ends thereof attached to a central stud L², thereby permitting either section to be detached and folded while the other section remains in position. This is desirable, as there are occasions when it is convenient to use the curtains for protecting one seat and not the other.

In operation, to adjust the curtains for use, the pocket J is opened, the cable drawn out and attached to the stud L, and the curtains are then slid upon the cable to proper position, after which the cable is engaged with the guide K which holds it taut and in a position parallel to the lower edge of the "quarter". In storing the curtains the cable is first detached from the guide K so as to permit sliding of the curtains to the extreme rear of the canopy and into the plane of the top thereof. In this position they are in registration with the pocket J and may be stored therein. The end of the cable is then detached from the stud and the crimps will facilitate the folding in proper lengths for storage in the pocket.

40 What I claim as my invention is:—

1. The combination with a vehicle canopy top having a depending "quarter" of a curtain, a storage pocket for said curtain beneath the canopy top, and a cable on which said curtains are strung extending from said pocket downward to the lower edge of the "quarter," and parallel to the latter, the curtain being slidably displacable on to the inclined portion of the cable to permit of its disposal in the storage pocket.

2. The combination with a vehicle canopy top having a depending "quarter" of side curtains therefor, a cable on which said curtains are strung having one end attached adjacent to the plane of the top of the canopy, and a guide with which said cable is detachably engaged for holding the main portion thereof parallel to and substantially in the plane of the lower edge of the "quarter," the curtains being slidable upon said cable to a position adjacent the canopy top, subsequent to disengagement of the cable from said guide.

3. The combination with a vehicle canopy having an inclined rear bow and a depending "quarter," of side curtains, a cable on which said curtains are strung extending parallel to the lower edge of said "quarter" and having an extension to the cross-bar of said rear bow, and a guide with which said cable is detachably engaged for holding the suspension portion parallel to and substantially in the plane of the lower edge of said "quarter."

4. The combination with a vehicle canopy provided with an inclined rear bow having its cross-bar in the plane of the canopy top and a depending "quarter," of a cable extending parallel to the side, curtains strung upon said cable, a guide on the inclined portion of said rear bow for holding said cable below the plane of the canopy top and substantially in the plane of the lower edge of said "quarter," and an extension of said cable beyond said guide attached to the cross-bar of the bow on which said curtains may be slid to storage position.

5. The combination with a vehicle canopy having an inclined rear bow with its cross-bar in the plane of the canopy top and a depending "quarter," of a curtain storage pocket secured to said cross-bar, a cable extending from said pocket substantially in the plane of the canopy top, down the inclined portion of the bow and horizontally parallel to the lower edge of the "quarter," a guide on said bow with which said cable is detachably engaged for holding the same in position, and curtains strung upon said cable and movable thereon into engagement with said storage pocket when said cable is detached from said guide.

6. The combination with a vehicle canopy, of a curtain storage pocket, side curtains, and a cable on which said curtains are strung extending parallel to the side and on to said storage pocket, said cable being detachable to permit of storage in said pocket.

7. The combination with a vehicle canopy, of a curtain-storage pocket extending across between the sides of said canopy, side curtains, and a cable on which said curtains are strung having one end secured adjacent to said storage-pocket and the opposite end detachably secured to the side of the canopy permitting of folding and storage in said pocket.

8. The combination with a vehicle canopy, of side curtains therefor, a storage-pocket for said curtains, a cable on which said curtains are strung extending from said storage pocket parallel to the side of the canopy and detachably attached thereto, said cable being crimped to facilitate the folding of the same.

9. The combination with a vehicle canopy,

of side curtains therefor, and a cable on which said curtains are strung formed in two sections extending respectively from rear and front to a point of attachment at the side and permitting of the independent use of the forward and rear curtains.

In testimony whereof I affix my signature in presence of two witnesses.

FRANK H. ILSE.
